UNITED STATES PATENT OFFICE.

GEORGE WALLACE STRUBLE AND WILLIAM L. LUKENS, OF BETHLEHEM, PENNSYLVANIA, ASSIGNORS TO BETHLEHEM STEEL COMPANY, OF SOUTH BETHLEHEM, PENNSYLVANIA, A CORPORATION OF PENNSYLVANIA.

PERCUSSION-FUSE FOR PROJECTILES.

1,189,403.

Specification of Letters Patent.

Patented July 4, 1916.

Application filed March 15, 1916. Serial No. 84,435.

To all whom it may concern.

Be it known that we, GEORGE WALLACE STRUBLE and WILLIAM LESLIE LUKENS, citizens of the United States, and residents of 5 Bethlehem, Northampton county, and Bethlehem, Lehigh county, respectively, State of Pennsylvania, have invented certain new and useful Improvements in Percussion-Fuses for Projectiles, of which the following 10 is a specification.

This invention relates to fuses for exploding projectiles and more particularly to safety devices for percussion fuses.

The principal object of the invention is 15 to provide a fuse of this class in which the bursting charge of the projectile is prevented from being ignited prematurely, even though the primer be accidentally detonated.

20 The invention will be described in connection with the accompanying drawings, in which,

Figure 1 is a longitudinal sectional view 25 of a fuse embodying our invention, the parts being shown occupying their relative positions before the impact of the shell; Fig. 2 is a similar view showing the relative positions of the parts after impact; and Fig. 3 is a horizontal cross-section along the 30 line 3—3 of Fig. 1.

Referring to the drawings, it will be seen 35 that the fuse comprises three main parts, namely, the body 10, the removable tip 11 and the removable stock 12 at the lower end 40 of the body. The tip 11 and the stock 12 are threaded into the opposite ends of a cylindrical opening which extends axially through the body of the fuse, the diameter of this passageway being varied at different 45 places. The upper end of this opening forms an enlarged cylindrical plunger chamber 13. The tip 11 is removably secured to the body by means of a boss 14 threaded into the upper end of the chamber 13 and stock 12 is likewise threaded into the lower end of the axial opening in the body. Within the chamber 13 is a plunger 15 which 50 is normally spring seated on the bottom of the chamber by a coiled spring 16 but which is free to move forward when the projectile is suddenly arrested. The plunger 15 has a rearward axial extension 17 fitting and sliding in a contracted part of

the axial opening, for a purpose to be presently explained.

55

Intersecting the contracted part of the axial opening, and arranged at right angles thereto, is a second cylindrical opening 18 which extends from the outer surface of the fuse about three-quarters of the distance through the fuse and which is of uniform diameter throughout. This opening 18 is formed in or near the plane of the screw threads 19, on the outer surface of the fuse body, by means of which the fuse 60 is secured in the point of the projectile, so that when the fuse is so secured within the projectile the mouth of the opening 18 is closed and protected by the wall of the projectile, as indicated by dotted lines in Fig. 1. 65 Located in this opening are the primer 20 and the hammer 21 for detonating the primer. The hammer 21 is tubular and is of considerable length, having only a comparatively short play between the inner end 70 of the opening and the primer 20, which is screw threaded into the outer end. The outer end of the hammer 21 has a plug 22 screw threaded therein, on which is formed a firing pin 23 which is adapted to explode 75 the primer when the hammer is actuated. Flash ports 24 are also provided in the plug 22 so that the flash from the primer may pass into the interior of the hammer. A partition 25 divides the interior of the hammer into two chambers, the forward chamber 26 being adapted to form a portion of the flame conduit between the primer and the bursting charge, while the rearward chamber 27 forms a container for the coil 80 spring 28 which bears against the end wall of the opening 18 and the partition 25 and normally tends to force the hammer 85 against the primer 20.

Extending diametrically through the partition 25 in the hammer is an opening 29 which serves as a part of the flame conduit from the primer to the bursting charge and to receive the extension 17 of the plunger 90 to act as a retainer for the hammer and a valve to close the flame conduit. In the wall between the opening 29 and the chamber 26 there is an opening 30 which is normally closed by the extension 17, as shown 95 in Fig. 1.

The function of the opening 29 is two-

105

fold, as it forms part of the flame conduit between the primer and bursting charge and by receiving therein the downwardly extending portion 17 of the plunger 15, it co-acts therewith to form part of the latching means which withholds the hammer from the primer at all times except on the impact of the shell.

As before explained, the plunger 15 is normally held seated on the bottom of the chamber 13 by the spring 16. When in this position the axial extension 17 of the plunger extends into the opening 29 at least a sufficient distance to completely close the port 30. This position of the parts is shown in Figs. 1 and 3 of the drawings. Immediately in front of the port 30 in the chamber 26 are two disks 32 and 33 of tinfoil and brass, respectively, or any other preferred form of obturator which are maintained in a vertical position to close the port by any suitable means. These disks coact with the extension 17 of the plunger to keep the flame from the primer from passing the port 30 and igniting the bursting charge upon accidental detonation of the primer. Without the support of the extension 17 the disks 32, 33 will not seriously impede the progress of the flame.

Arranged axially of the fuse and immediately under the hammer 21 is a flash port 34 of such diameter that the opening 31 in the hammer communicates therewith when the hammer has moved toward the right to fire the primer, as shown in Fig. 2. Under the flash port 34 is a cylindrical cavity 35 arranged centrally in the upper end of the stock 12 and which is adapted to contain a powder pellet. A duct or conduit 36 extends downwardly from this cavity 35 through the stock and has an opening in contact with the bursting charge of the projectile. Clamped between the stock 12 and the fuse body 10 and arranged to separate the flash port 34 and the cavity 35 is a shellac coated muslin disk 37, which keeps powder from the powder pellet from passing upwardly and hindering the free action of the hammer. The disk 37, however, will not prevent the passage of flame therethrough to ignite the powder pellet. In order that the hammer be not impeded in its firing movement by the formation of a partial vacuum behind it, holes 38 are made in the cylindrical wall thereof behind the partition 25 so that air may have ready ingress.

From the above description the operation of our invention will be apparent and it will only be necessary to refer to it briefly. While the projectile is in storage and during flight when fired from a gun, the positions of the hammer and plunger are as shown in Figs. 1 and 3, the plunger performing the double function of holding the hammer in its retracted position and of

closing the flash port 30. When in this position accidental ignition of the primer cannot explode the projectile as the flame from the primer will be confined to the chamber 26. The spring 16 is of such strength that no ordinary jar, such as may occur in transporting or handling the projectile, will compress the spring and release the hammer. When the projectile strikes a solid object, however, the momentum of the plunger 15 will carry it forward, compressing the spring 16 and opening the flash port 30 and releasing the hammer 21. The hammer is immediately forced to the right by the spring 28 and the firing pin 23 contacts with and explodes the primer 20. The flash from the primer 20 instantly passes through the conduit, which has thus opened between the primer and the powder pellet, and ignites the latter. The disks 32, 33 yield to the pressure when the port 30 is opened and the muslin disk is consumed or burst. The flash from the powder pellet in turn travels through the duct or conduit 36 and ignites the bursting charge of the projectile.

From the foregoing description it is apparent that our improved fuse is simple and easy to construct, certain of operation, and will prevent at all times bursting of the projectile due to the premature ignition of the primer.

Having thus described the invention what is claimed and desired to be secured by Letters Patent is:—

1. A percussion fuse for projectiles comprising a body having an axial opening therein and a radial opening intersecting the axial opening, a hammer in the radial opening having a longitudinal flame passage and having a transverse perforation adapted to align with the radial opening, a plunger in the axial opening arranged to normally extend into the perforation in the hammer to lock the hammer and close the flame passage, a primer in front of the hammer, and a spring in the rear of the hammer.

2. A percussion fuse for projectiles comprising a body having an axial opening therein and a radial opening intersecting the axial opening, a hammer in the radial opening having a longitudinal flame passage and having a transverse perforation adapted to align with the radial opening, a plunger in the axial opening arranged to normally extend into the perforation in the hammer to lock the hammer and close the flame passage, an obturator arranged in said flame passage adjacent said plunger, a primer in front of the hammer, and a spring in the rear of the hammer.

3. A percussion fuse for projectiles comprising a body having an axial opening therein and a radial opening intersecting the axial opening, a hammer in the radial open-

ing having a longitudinal flame passage and having a transverse perforation adapted to align with the radial opening, a plunger in the axial opening arranged to normally extend into the perforation in the hammer to lock the hammer and close the flame passage, an obturator comprising a thin metal disk ar-

ranged in said flame passage adjacent said plunger, a primer in front of the hammer, and a spring in the rear of the hammer. 10

In testimony whereof we affix our signatures.

GEORGE WALLACE STRUBLE.

WILLIAM L. LUKENS.
